BOTTLE CLOSURE

George H. Hutaft, Jr., Wilmington, N. C.

Application April 14, 1938, Serial No. 202,043

5 Claims. (Cl. 215—39)

My invention relates to new and useful improvements in bottle closures, in general appearance similar to the so-called crown cap type and has for its principal object the provision of the device of the character described which is relatively simple in construction, provides a tight seal for closing the mouth of the bottle, and may be readily removed without use of the usual form of bottle cap remover, the fingers of the user being normally sufficient for removing the closure although a knife, coin or similar object may be used where found desirable.

A further object of the invention resides in the provision of a closure of the character described which includes a plurality of separately removable cap portions, the cap portions being superposed so that they may be successively removed.

Another object of the invention consists in the provision of a closure of the character described including a plurality of separately removable cap portions, at least one of the cap portions being formed to permit tearing of a portion thereof.

Still another object of the invention resides in the provision of a closure of the character described including a plurality of separately removable superposed cap portions, certain of the cap portions being adapted for use as a lever in removing the cap portion therebeneath.

With the above and other objects in view, which will appear as the description proceeds, my invention consists in the novel details of construction, and arrangement of parts, described in the following specification and illustrated in the accompanying drawings, and while I have illustrated and described the preferred embodiments of the invention, as they now appear to me, it will be understood that such changes may be made as will fall within the scope of the appended claims.

In the drawings—

Fig. 1 is a plan view showing three cap portions used for forming my improved closure, two of the cap portions having circular tear-out sections.

Fig. 2 is a longitudinal vertical section through Fig. 1.

Fig. 3 is a section on the line 3—3 of Fig. 2 looking in the direction of the arrows.

Fig. 4 is a section on the line 4—4 of Fig. 2 looking in the direction of the arrows.

Fig. 5 is a top plan of the completed closure with the cap portions folded into superposed position.

Fig. 6 is a side elevation of the closure shown in Fig. 5.

Fig. 7 is a transverse vertical section on the line 7—7 of Fig. 5.

Fig. 8 is a fragmental section showing the closure disclosed in Figs. 5 to 7 inclusive applied to the mouth of a bottle, the closure being illustrated in side elevation.

Figs. 9 to 16 inclusive show diagrammatically positions and portions of the cap portions in the act of being removed and after removal from the 10 bottle mouth.

Fig. 17 is a plan showing three cap portions adapted to be folded to provide a different form of my invention and in which two of the cap portions are provided with circular tear-out sections.

Fig. 18 is a side elevation of that form of my invention disclosed in Fig. 17.

Fig. 19 is a fragmental detail showing the closure formed from the cap portions shown in Figs. 17 and 18 of the drawings, applied to the bottle 20 mouth.

Figs. 20 to 24 inclusive show diagrammatically the positions and portions of the cap portions when being removed from the bottle mouth.

Fig. 25 is a plan illustrating three cap portions 25 adapted to be folded to provide another form of closure, the intermediate cap portion having a circular tear-out section.

Fig. 26 is a side elevation of that form of the invention disclosed in Fig. 25.

Fig. 27 is a side elevation showing the three cap portions of Figs. 25 and 26 folded to superposed position.

Figs. 28 to 31 inclusive show diagrammatically the manner of removing the cap portions of Figs. 35 25 and 26.

Fig. 32 is a plan of three cap portions used for providing another form of my invention, the flange of the intermediate cap portion being formed to permit a section to be torn circumferentially therefrom.

Fig. 33 is a side elevation of that form of the invention disclosed in Fig. 32.

Figs. 34 and 35 show diagrammatically the manner of removing the cap sections of Figs. 32 and 33.

In Figs. 1 to 16 inclusive of the drawings I have illustrated a form of my closure which is formed of three cap portions shown at 1, 2 and 3 each of these cap portions being formed of a top and circuit flange, the flange of the portion 1 being of less height than the flanges of the portions 2 and 3, as shown more particularly in Fig. 2 of the drawings and the purpose of which will be presently brought out. The cap portions 1 and 2 are connected by the strip 4 whereas the cap portions

2 and 3 are connected by the strip 5. As shown more particularly in Figs. 1 and 2 of the drawings when the cap portions are initially formed the end portions will be in a reversed position to the intermediate portion 2. The cap portion 2 is formed with the cut-out 6 which forms the tab 7, this tab 7 being connected to the cap by means of the strip 8 which is intended to be torn along the perforated or weakened lines 9, these perforations or weakened lines extending throughout the height of the flange of the cap portion 2 and aligning with the edges of the strip 4. The cap portion 3 is formed with the cut-out 10 which provides the tab 11 connected to the cap by the strip 12 adapted to be torn along the weakened or perforated lines shown at 13. These perforated or weakened lines 13 extending throughout the height of the flange of the cap portion 3 and aligned with the edges of the strip 5 as shown more particularly in Fig. 1 of the drawings. To form the closure the cap portion 3 is adapted to be folded over and into the cap portion 2. The cap portion 1 is adapted to be folded under and receive the cap portion 2. The positions of these folded cap portions are shown more particularly in Figs. 5, 6 and 7 of the drawings and it will be seen that the caps will be superposed when applied to the mouth of the bottle, the mouth of the bottle being illustrated at 14 in Fig. 8 of the drawings. When the cap portions have been superposed, as shown, the flanges will be crimped as shown at 15 and the assembled parts will be of the shape of the well-known crown type of cap and adapted to be applied to the bottle mouth by the usual form of capping device. As is quite clearly illustrated in Figs. 6 and 7 of the drawings the flange *a* of the cap portion 1 terminates above the bottom edges of the flanges of the cap portions 2 and 3.

As I have stated in the objects of my invention I desire to provide a closure which may be removed from the bottle mouth without the usual form of bottle cap remover. Very often such cap removers become misplaced and are of such a size that they cannot readily be carried in the pockets of a user. Ordinarily my improved form of closure may be removed by the fingers of the user but should it be found necessary a knife blade or coin, usually carried in the pockets, may be used. When it is desired to remove that form of closure disclosed in Figs. 1 to 16 inclusive of the drawings the user will engage the bottom edge of the flange *a* of the cap portion 1 and raise the same into the position shown in Fig. 9 of the drawings. Then with an upward pull on this cap portion, as shown more particularly in Fig. 10 of the drawings, the connecting strip 4 will tear the strip 8 along the weakened or perforated lines 9 until the cut-out 6 is reached when the tab 7 will be removed as shown in Fig. 11 of the drawings. This leaves the ring-like portion of the cap 2 to be readily raised into the position shown in Fig. 12 of the drawings and then when pulling upwardly, as shown in Fig. 13, the connecting strip 5 will tear the strip 12 along the weakened lines or perforations 13 until the cut-out 10 is reached and then the tab 11 will be removed as shown in Fig. 14 of the drawings. This leaves the ring-like portion of the cap 3, which I have indicated at *b*, in the position shown on the bottle mouth in Fig. 15 and this ring-like portion may be sprung apart for removal from the mouth of the bottle. The removed ring-like portion is shown in Fig. 16 of the drawings.

It will thus be seen from the above that I

have provided a bottle closure which may be readily applied to the mouth of the bottle and easily removed therefrom without the use of the well-known form of bottle cap remover. The cap portion 1 does not have any openings therein and therefore the openings or cut-outs 6 and 10 of the cap portions 2 and 3 respectively are closed and no leakage is permitted therethrough. The closure may be formed of readily thin material so that when the three cap portions are superposed they need not be of greater thickness or weight than the usual form of cap now used for sealing bottle mouths.

In Figs. 17 to 24 inclusive of the drawings I have shown another form of my invention which is quite similar to that disclosed in Figs. 1 to 16 inclusive in that it embodies the use of three cap portions which I have indicated at 16, 17 and 18, the cap portion 16 being connected to the cap portion 17 by means of the strip 19 whereas the cap portion 17 is connected to the cap portion 18 by means of the strip 20. Each of the cap portions includes a top and circumferential flange, the flange of the cap portion 18 being of less height than the flanges of the cap portions 16 and 17 as illustrated more clearly in Fig. 18 of the drawings. The cap portion 16 is provided with the cut-out 22 which forms a tab 23 connected to the cap by means of the strip 24, this strip 24 being adapted to be torn along the weakened lines or perforated lines 25, the lines extending over the top of the cap portion and throughout the height of the flange, as shown more particularly in Fig. 17 of the drawings. The perforated or weakened lines 25 align with the side edges of the strip 19 and also aligning with the edges of the strip 19 are the perforations or weakened lines 26 formed in the cap portion 17 and which extend throughout the height of the flange of this cap portion and over the top surface thereof to the cut-out portion 27 which forms the tab 28. The cap portion 18 is adapted to be folded over and into the cap portion 17 whereas the cap portion 16 is adapted to be folded under and over the cap portion 17. When thus folded the cap portions provide a closure of the well-known crown cap type and the closure is adapted to be placed on the bottle mouth 29 by use of a well-known form of capping device. It will be seen that the cap portion 18 provides a seal for the cut-outs 22 and 27 formed in the cap portions 16 and 17 respectively.

When it is desired to remove this form of cap, just described, from the bottle mouth 29 the user engages his nails or a knife blade or coin or the like beneath the tab 23 of the cap portion 16 and then raises the same, as shown more particularly in Fig. 20 of the drawings. By pulling upwardly and downwardly on the tab the strip 24 is torn along the weakened or perforated lines 25 and thereby forms simply a ring-like portion which may be readily removed from the cap portion 17. Then by using the tab portion 23, as a lever, and pulling upwardly thereon, as shown more particularly in Fig. 21 of the drawings, the strip 19 is torn along the perforated or weakened lines 26 and removes the tab 28 from the cap portion 17, as shown more particularly in Fig. 22 of the drawings. Then the ring-like portion of the cap 17 formed by the removal of the tab or strip 19 may be used as a lever for removing the cap portion 18 as shown more particularly in Fig. 24 of the drawings.

In Figs. 25 to 31 inclusive I have shown another form of my invention in which three cap portions

are provided to form the complete closure, these cap portions being illustrated at 109, 110 and 111. As is shown quite clearly in Fig. 26 of the drawings the flanges 112 and 113 of the cap portions 109 and 111 respectively are of less width than the flange 114 of the cap portion 110. The cap portion 109 is connected to the cap portion 110 by means of the strip 115 whereas the cap portion 110 is connected to the cap portion 111 by means of the strip 116. The cap portion 110 is provided in its top with the cut-out tab 117 connected by the strip 118 which is adapted to be torn along the weakened or perforated lines 119 extending across a portion of the top of the cap and downwardly through the flange 114 thereof and in alignment with the edges of the connecting strip 115 as is quite clearly illustrated in Fig. 25 of the drawings. In forming the closure the cap portion 109 is folded beneath the cap portion 110 when in the position shown in Fig. 26 and the cap portion 111 is folded over and into the cap portion 110. When thus superposed the caps may be positioned on the bottle mouth by the usual form of capping mechanism. The assembly of the caps is shown in Fig. 27. When it is desired to remove the closure from the bottle mouth the edge of the cap portion 109 is engaged and the cap bent upwardly into the position shown in Fig. 28 of the drawings. The cap is then used as a lever to pull up on the strip 115 and this tears the strip 118 from the cap 110, as shown more particularly in Fig. 29 of the drawings and removes the tab 117, as shown more particularly in Fig. 30 of the drawings. Then the ring-like or flange portion 114 of the cap 110 is raised into the position shown in Fig. 31 of the drawings and is used as a lever for removing the cap portion 111 from the bottle mouth.

In Figs. 32 to 35 inclusive of the drawings I have shown a still further form of my device in which, as in Figs. 25 to 31 inclusive, the closure is formed from three cap portions, these cap portions being illustrated at 120, 121 and 122, the flange portions 123 and 124 of the caps 120 and 122 respectively being of less width or height than the flange 125 of the cap 121. The cap 120 is connected to the cap 121 by means of the strip 126 and the cap 121 is connected to the cap 122 by means of the strip 126. The flange 125 of the cap 121 is provided with a weakened or perforated line 127 which extends circumferentially of the flange for a portion thereof with one end of the line terminating adjacent an edge of the connecting strip 126 as shown more particularly in Fig. 32 of the drawings. The complete closure is formed by folding the cap 120 under the cap 121 when in the position shown in Fig. 33 and the cap 122 over and into the cap 121. The flanges 123 and 124 of the cap portions 100 and 122 respectively will overlie the perforated line 127 and prevent leakage therethrough. The superposed cap portions, as a unit, will be applied to the bottle mouth by the usual form of capping device.

When it is desired to remove the form of closure shown in Figs. 32 to 35 inclusive the cap 120 will be raised and by pulling thereon a portion of the flange 125, of the cap portion 121, will be torn and removed as shown in Fig. 34 of the drawings. The cap 121 will then be engaged and by pulling thereon the cap 122 may be pulled from the bottle mouth.

I wish it understood that in order to provide a tight seal at the bottle mouth the innermost

cap of each of the forms of closure illustrated will be provided with the usual form of cork or other disc. It will also be understood that in each form of the closure the flanges of the cap portions will be crimped although in some of the views this is not shown for the sake of clearness.

In view of the fact that in connection with each of the forms of my invention I have described the manner in which they are formed as well as the manner in which they are removed from the bottle mouth a further detailed description is not thought necessary at the present time. It will be noted that, as stated in the objects of the invention, I have provided a bottle closure which includes a plurality of separately removable cap portions, the cap portions being superposed and in each instance or each form of the invention at least one of the cap portions being formed to permit tearing of a portion thereof. While I have illustrated several different forms of the invention the principle is the same in each instance and each form is such that it may be removed from a bottle mouth without the use of the ordinary form of bottle cap remover. It can be appreciated that at times the usual form of bottle cap remover is not available for various reasons and while the several forms of my closure may be removed by the fingers of the user if found desirable a knife blade, coin, or the like may be used. Such are ordinarily found in the pocket of a user or one desiring to open a bottle.

Having fully described my invention what I claim as new and desire to secure by Letters Patent is:

1. A closure for bottles or the like including top, bottom and intermediate cap portions telescoped one within the other, means connecting the top cap portion with the intermediate cap portion and the intermediate cap portion with the bottom cap portion, the top cap portion being adapted for use as a lever for tearing a part of the intermediate cap portion to remove the same from the bottle and the remaining part of the intermediate cap portion being adapted for use as a lever for tearing away a part of the bottom cap portion for removing the same from the bot-

2. A closure for bottles or the like including top, bottom and intermediate cap portions telescoped one within the other, the intermediate and bottom cap portions being formed with tear-out parts, means connecting the top cap portion with the intermediate cap portion and the bottom cap portion, the top cap portion being adapted for use as a lever for removing the tear-out part of the intermediate cap portion to remove the same from the bottle and the remaining part of the intermediate cap portion being adapted for use as a lever for removing the tear-out part of the bottom cap portion for removing the same from the bottle.

3. A closure for bottles or the like including top, bottom and intermediate cap portions telescoped one within the other, the top and intermediate cap portions being formed with tear-out parts, and means connecting the top cap portion with the intermediate cap portion and the intermediate cap portion with the bottom cap portion, the tear-out part of the top cap portion being adapted for removal to remove the top cap portion from the bottle and to act as a lever for removing the tear-out part of the intermediate cap portion to remove that cap por-

portion from the bottle, the intermediate cap portion remaining after the tear-out part is removed being used as a lever for removing the bottom cap portion from the bottle.

4. A closure for bottles or the like including top, bottom and intermediate cap portions telescoped one within the other, means connecting the top cap portion with the intermediate cap portion and the intermediate cap portion with the bottom cap portion, the intermediate cap portion having a tear-out part adapted to be removed by using the top cap portion as a lever, and the remaining part of the intermediate cap portion being adapted for use as a lever in removing the bottom cap portion.

5. A closure for bottles or the like including

top, bottom and intermediate cap portions telescoped one within the other, means connecting the top cap portion with the intermediate cap portion and the intermediate cap portion with the bottom cap portion, the intermediate cap portion being formed with a weakened or perforated line in its depending flange, the flange of the intermediate cap portion being adapted to be torn along its weakened or perforated line by removal of the top cap portion and using the same as a lever, the torn flange permitting the removal of the intermediate cap portion, and the removed intermediate cap portion being used as a lever for removing the bottom cap portion.
